(57) **CLAIM**

The ornamental design for a kitchen faucet, as shown and described.

DESCRIPTION

The file of this patent contains at least one drawing/photograph executed in color. Copies of this patent with color drawings/photographs will be provided by the Office upon request and payment of the necessary fee.

FIG. 1 is a top and front side perspective view of a kitchen faucet showing my new design;

FIG. 2 is a bottom and rear side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The part of the photograph shown in broken lines perimeter, as well as the broken-line perimeter itself, illustrate portions of the kitchen faucet that form no part of the claimed design.
